FISHING TACKLE CONTAINER

Verlis H. Wiley, Kenmore, N. Y.

Application February 25, 1955, Serial No. 34,722

Term of patent 14 years

(Cl. D58—11)

Fig. 1.

Fig. 2.

Fig. 4.

Fig. 1 is a perspective view of a fishing tackle container embodying my new design;

Fig. 2 is a perspective view thereof, shown in open position;

Fig. 3 is a side elevational view thereof; and

Fig. 4 is an end elevational view thereof.

I claim:

The ornamental design for a fishing tackle container, substantially as shown.
